UNITED STATES PATENT OFFICE.

CLINTON B. KEITH, OF WEST FRANKFORT, ILLINOIS.

ICE-SHAVING MACHINE.

Application filed August 13, 1924. Serial No. 731,805.

To all whom it may concern:

Be it known that I, CLINTON B. KEITH, a citizen of the United States, residing at West Frankfort, in the county of Franklin 5 and State of Illinois, have invented new and useful Improvements in Ice-Shaving Machines, of which the following is a specification.

This invention relates to an ice cutting machine, the general object of the invention being to provide a casing for containing a block of ice and receptacles for liquids to be cooled with means for cutting shavings or small pieces from the block of ice when desired without removing the block from the casing.

Another object of the invention is to provide power means for operating the cutting means and feeding means operated from the power means for pushing the block against the cutting means.

A further object of the invention is to provide auxiliary cutting means for breaking up any large pieces broken from the block.

This invention also consists in certain other features of construction and in the combination and arrangement of the several parts, to be hereinafter fully described, 30 illustrated in the accompanying drawings and specifically pointed out in the appended claims:

In describing my invention in detail, reference will be had to the accompanying 35 drawings wherein like characters denote like or corresponding parts throughout the several views, and in which:

Figure 1 is an elevation with parts broken away of the invention.

Figure 2 is a section on line 2—2 of Figure 1.

Figure 3 is a detail plan view of the outlet means.

Figure 4 is a view of one of the cutting knives.

Figure 5 is a view of the ratchet means on the feeding bar.

Figure 6 is a view of the means for operating the ratchet means from the power means.

Figure 7 is a horizontal section on line 7—7 of Figure 1.

Figure 8 is a section on line 8—8 of Figure 1.

Figures 9 and 10 are detail views of cutters which may be used with the device.

In these views, 1 indicates a casing which is supported from the legs 2 and which is shaped to receive a block of ice, such as shown at A, and the liquid containers B, the 60 contents of which will get cooled by the ice. The containers B are provided with the faucets 3 which extend through the casing and with the tops 4 which are clamped in position by the nuts 5. The casing is provided with a cover 6 which is provided with a liquid seal, as shown at 7. Slats 8 are placed in the bottom of the casing and upon which the block rests so that the block can be easily moved in the casing. An extension 70 9 is formed at one end of the casing and a shaft 10 passes through the extension and is connected with the shaft of a motor 11 supported by the hanger 12 supported from the bottom of the casing. A gear casing 13 is 75 pivoted to this shaft and this casing rotatably supports a vertical shaft 14 which is geared to the shaft 10 by the gears 15. A shaft 16 is rotatably mounted in the lower part of the extension 9 and is connected with 80 the shaft 10 outside of the extension by the gears 17. A crank disc 18 is fastened to the shaft 16 and the crank pin thereof engages a slot 19 in an arm 20 which depends from the casing 13, the parts being so arranged 85 that as the shaft 16 rotates the pin 18 engaging the slot 19 will cause the gear casing and the shaft 14 to oscillate as will be understood. The upper end of the shaft 14 is 90 guided in its movement by the guideway 21 in the upper part of the casing and said shaft is provided with the cutters 22 which are arranged to engage the end of the block of ice and thus shave small particles therefrom as the shaft oscillates and rotates. 95

These particles will drop into the extension 9 and pass therefrom through the chute 23 which is carried by the slide 24, operated by the handle 25. In one position of the parts the slide 24 will cover the outlet opening 100 and thus prevent discharge of ice from the device or the inlet of air thereinto and in the other position the chute 23 will be under the outlet opening so that the ice can pass therethrough. The slide is provided with a water seal 25' and is supported vertically by the pins 26 so that in its closed position it will be raised to make active the water seal. The handle is fastened to a switch 27 which controls the circuit to the motor 11 so 105 that when the slide is closed the circuit of the motor will be broken. The shaft 16 is 110

provided with the cutters 8 which operate in conjunction with the grate bars 29 placed below the same so that any large particles of ice dropping down the extension will be broken up by these cutters and grate bars. I may use different kinds of cutters 22, as shown in Figures 9 and 10, where the cutter 22 is used for shaving the ice, while the cutter 22' is used for cutting small particles about the size of hail from the ice. These cutters are provided with square openings for fitting over the square portion of the shaft.

The means for feeding the block of ice against the cutter comprises a screw shaft 29 placed in the bottom of the casing and engaged by a movable nut member 30 which is attached to a feed plate 31 in the casing and which is designed to engage the rear end of the block of ice. This plate slides on the two guide bars 32 and by lifting up the nut member 30 it will be freed of the shaft so that the push plate can be pulled back to its starting point without turning the shaft. The shaft can be turned by the hand wheel 33 though I prefer to turn it from the motor through means of a lever 34 pivoted to the extension 9 and having a projection 35 thereon engaged by a cam 36 on the outer end of the shaft 16 so that the lever 34 is rocked at each revolution of the shaft 16. The upper end of the shaft is connected by a chain 37 with a lever 38 pivoted to the bottom of the casing, as at 39, and having its front end connected by a chain 40 with a sliding dog 41 which engages a ratchet 42 on the shaft 29, springs 43 and 44 tending to return the parts to normal position. Thus at each revolution of the shaft 16 the lever 38 is rocked to pull the dog 41 into engagement with the ratchet 42 to rotate the same one step and thus turn the shaft 29. This turning movement of the shaft will be communicated to the feed plate 31 by means of the nut 30.

From the foregoing it will be seen that ice can be shaved from the block or small particles cut therefrom, according to the kind of knives used, and these particles dropping through the extension 9 will be discharged through the chute 23 when the same is in operative position. The cutting action results from the reciprocatory movement of the shaft 14 and the rotary movement thereof. When the cutting action is taking place the ice is fed step by step towards the cutting means and the parts are so timed that the cutting shaft is at one end of its limit of movement before the feeding action takes place so that the ice block is not contacting with the cutters when the parts are at rest as the ice will not be fed against the cutters until the cutter bar starts on its return movement.

It is thought from the foregoing descrip-

tion that the advantages and novel features of my invention will be readily apparent.

I desire it to be understood that I may make changes in the construction and in the combination and arrangement of the several parts, provided that such changes fall within the scope of the appended claims.

What I claim is:

1. A device of the class described comprising a casing for holding a block of ice, feeding means therein, a cutting bar, means for oscillating the bar and rotating the same across the end of the block and means for operating the feeding means as the cutter bar finishes its stroke. 75

2. A device of the class described comprising a casing for holding a block of ice, feeding means therein, a cutting bar, means for oscillating the bar and rotating the same across the end of the block, means for operating the feeding means as the cutter bar finishes its stroke and auxiliary cutting means under the first means for cutting any large pieces of ice that are knocked off the block by the first means. 80

3. A device of the class described comprising a casing for holding a block of ice, feeding means therein, a cutting bar, means for oscillating the bar and rotating the same across the end of the block, means for operating the feeding means as the cutter bar finishes its stroke, auxiliary cutting means under the first means for cutting any large pieces of ice that are knocked off the block by the first means and a single motor operating both the cutting means and the feeding means. 90

4. A device of the class described comprising a casing for receiving a block of ice, a screw shaft in the casing, a push plate in the casing, a movable nut member connected with the push plate and engaging the spiral shaft, ratchet means for giving the shaft a step by step movement, a shaft journaled in a part of the casing, a motor connected with the shaft, a gear casing rotatably mounted on the shaft, a vertically arranged cutter carried by the gear casing, gears connecting the two shafts together and arranged in the gear casing, cutters on said shaft, a shaft 110 having a crank thereon, a depending arm on the gear case engaging the crank so that the gear casing will be oscillated by the movement of the crank, means for driving the crank case from the motor shaft and means for operating the ratchet mechanism from the crank shaft. 115

5. A device of the class described comprising a casing containing a block of ice, a cutter bar therein, means for rotating the bar 125 and for oscillating it across one end of the block of ice, a cover for the casing, a seal therefor, liquid receptacles in the casing, faucets therefor extending through the casing, a closure member for the outlet opening 130

of the casing, a seal for the same and manually operated means for moving the closure means.

6. A device of the class described comprising a casing having a depending part at one end thereof, means for supporting a block of ice in the casing, means for feeding the block towards one end of the casing, a cutter

shaft extending into the depending part of the casing, means for oscillating the same and for rotating it as it oscillates, an auxiliary cutter shaft, grate-like cutter bars associated with the cutters of the auxiliary shaft and a single motor for operating the parts.

In testimony whereof I affix my signature.

CLINTON B. KEITH.
